Primary Examiner — Cynthia Ramirez*Assistant Examiner* — Laura H Yu(74) *Attorney, Agent, or Firm* — Belles Katz LLC(57) **CLAIM**

The ornamental design for a swimsuit, as shown and described.

DESCRIPTIONFIG. 1 is a front view of a swimsuit showing my new design.
FIG. 2 is a rear view thereof.FIG. 3 is a left-side view thereof; and,
FIG. 4 is a right-side view thereof.

The dash-dot-dash lines immediately adjacent to the shaded area define the bounds of the claimed design and form no part thereof. The broken lines illustrating portions of the swimsuit form no part of the claimed design. All other broken lines illustrating the body are for environmental purposes only and form no part of the claimed design.

1 Claim, 4 Drawing Sheets(56)
